UNITED STATES PATENT OFFICE.

GEORGE B. DEXTER, OF BROOKLINE, MASSACHUSETTS.

DEVICE FOR RESTORING NAP TO FABRICS.

No. 857,088.

Specification of Letters Patent.

Patented June 18, 1907.

Application filed October 20, 1906. Serial No. 339,804.

To all whom it may concern:

Be it known that I, GEORGE B. DEXTER, a citizen of the United States, residing at Brookline, in the county of Norfolk and State of Massachusetts, have invented new and useful Improvements in Devices for Restoring Nap to Fabrics, of which the following is a specification.

This invention relates to improvements in devices for restoring nap to the surface of fabrics. When the nap of the fabric has been pressed down or worn off in the use of a garment, the appearance of said fabric is spoiled it being made shiny thereby and expedients employed to restore the original appearance to said fabric have failed either partially or wholly.

The object of this invention is to provide a simple inexpensive device by means of which nap may be easily and quickly restored to fabrics so that the appearance is like that of new fabric.

The invention consists in the combination and arrangement of parts set forth in the following specification and particularly pointed out in the claims thereof.

Referring to the drawings: Figure 1 is a plan view of the device of my invention. Fig. 2 is a section, partly in elevation, taken on line 2--2 of Fig. 1 looking in the direction of the arrows showing also a support and a piece of fabric in section, said device resting on said fabric. Fig. 3 is an enlarged section of a portion of Fig. 2. Fig. 4 is a section similar to Fig. 2, but showing the device with pressure applied downwardly, thereto. Fig. 5 is an enlarged section of a portion of Fig. 4. Fig. 6 is an enlarged detail perspective view of one of the teeth or dents.

Like numerals refer to like parts throughout the several views of the drawings.

In the drawings, 10 is a holder provided with two slots 11, 11 in one end thereof and two larger slots 12, 12 in the other end thereof. A suitable handle 13 is fast to the holder 10. A resilient member 14 preferably in the form of a convexly curved metal spring is provided with ears 15, 15 which are located in the slots 11, 11 and is also, provided with ears 16, 16 which are located in the slots 12, 12. A covering 17 formed of any suitable material such as composite material is fastened to the resilient member 14 by means of a plurality of rivets 18. A plurality of double pointed teeth or dents 19 are mounted on the resilient member 14 in the following manner.

Each of the teeth 19 consists of a piece of wire bent U-shaped as shown in Fig. 6, the free ends 20, 20 of said wire being forced through the covering 17, and when said covering is applied to the resilient member 14 the bases 21 of said teeth rest against the underside of said resilient member. The resilient member 14, the covering 17, and the teeth 19 thus form a very resilient structure. The free ends 20 of the teeth 19 are bent with relation to the remainder and extend away from the member 14 and are inclined at an angle thereto.

The operation of the device hereinbefore specifically described is as follows: A piece of fabric 22 is placed upon a support 23 and the device of my invention is placed thereon, as shown in Figs. 2 and 3. The user grasps the handle 13 and applies pressure thereto in the direction of the arrows, Figs. 2 and 3, the ears 16, 16 being free to play in the slots 12, 12 the resilient member 14 yields with relation to the holder 10 until it occupies the position shown in Figs. 4 and 5. The downward pressure on the handle 13 is then diminished, but the pressure toward the left is continued to a slight degree, the holder 10 being allowed to return to the position shown in Figs. 2 and 3. It will be seen by reference to Fig. 5 that when the pressure is applied to the handle 13 the sharp points of the free ends of the teeth 19 enter the fabric 22 to a slight degree and as said pressure is removed and pressure toward the left is maintained while the holder 10 moves upwardly the sharp points of the free ends 20 will act to restore to the fabric 22 its nap. Repetition of the described operation over such portions of the fabric 22 as may be desired, results in imparting to said fabric the appearance of a new piece of fabric. The great value of this device will be at once apparent for, as is well known, many garments which have become shiny through long continued use are often discarded when by the use of the device of my invention nap may be restored to the surface of the fabric, thus making the garments as good as new.

Having thus described my invention what I claim and desire by Letters Patent to secure is:

1. In a device of the character described a rigid holder, a handle fast thereto, a convexly curved spring mounted on said holder one end of said spring adapted to slide relatively thereto, a covering of sheet material for said

spring, and a plurality of teeth formed of wire inserted in said covering, the free ends of said teeth extending away from said spring and inclined at an angle thereto.

5 2. In a device of the character described, a holder provided with slots, a convexly curved spring mounted on said holder and adapted to yield relatively thereto, said spring provided with ears adapted to reciprocate in said 10 slots, and a plurality of teeth mounted on said spring, the free ends of said teeth extending away from said spring and inclined at an angle thereto.

3. In a device of the character described, a 15 holder provided with slots, a convexly curved spring mounted on said holder and adapted to yield relatively thereto, said spring provided with ears adapted to reciprocate in said slots, a covering of sheet material fast to said 20 spring, and a plurality of teeth formed of

wire inserted in said covering, the free ends of said teeth extending away from said spring and inclined at an angle thereto.

4. In a device of the character described, a holder provided with a slot, a convexly curved spring mounted on said holder and adapted to yield relatively thereto, said 25 spring provided with an ear adapted to reciprocate in said slot, and a plurality of teeth mounted on said spring, the free ends of said 30 teeth extending away from said spring and inclined at an angle thereto.

In testimony whereof I have hereunto set my hand in presence of two subscribing witnesses.

GEORGE B. DEXTER.
